(57) **CLAIM**

The ornamental design for a tire as shown and described.

DESCRIPTION

FIG. 1 is a perspective view of a tire according to the new design, it being understood that the pattern is repeated uniformly throughout the circumference of the tread.

FIG. 2 is a front view thereof. The top and bottom views are identical to the front view of FIG. 2.

FIG. 3 is a rear view thereof.

FIG. 4 is a left side view thereof.

FIG. 5 is a right side view thereof; and,

FIG. 6 is a detailed view from upper 6-6 to lower 6-6 of FIG. 2.

The broken lines are disclaimed and form no part of the claimed design. The dash-dot-dash lines show a boundary of the claimed area and are not themselves part of the claimed design. The surface shading lines and stippling in the drawings depict the character or contour of the surfaces represented and are not themselves part of the claimed design.
